UNITED STATES PATENT OFFICE.

CHARLES RINGEL, OF NORTH HAWTHORNE, NEW JERSEY, ASSIGNOR TO THE SUPER-HEATER COMPANY, OF NEW YORK, N. Y.

THROTTLE VALVE.

Application filed December 16, 1926. Serial No. 155,285.

My invention relates to locomotive throttle valves and is an improvement upon the type of valve disclosed in Reissue Patent No. 16,285, granted March 9th, 1926, to R. M. Brown.

In the type of valve disclosed in the above patent wherein the steam passing to the locomotive engine is controlled by a series of poppet valves located in the header of a superheater, considerable difficulty has been experienced in lifting these valves against the pressure of steam in the boiler, and it has been suggested, as, for example, in the application of R. M. Brown, Serial Number 24,802, filed April 21st, 1925, that this difficulty be overcome by the balancing of these valves through the medium of a suitable balancing chamber cast in the superheater header, in which balancing pistons for the several valves are arranged.

The present invention has for its principal object the provision of a novel form of balanced valve suitable for incorporation in a superheater header which will eliminate the difficulties heretofore encountered because of the expansion and contraction of the walls of the header under different conditions. A further object of the invention is the provision of a balanced valve mechanism, the several elements of which may be readily removed from the header either singly or as a unit. Other and more detailed objects of the invention and the advantages to be derived from the use thereof will appear more fully in connection with the detailed description of a preferred embodiment of the invention which I have illustrated in the accompanying drawings, in which Fig. 1 is a fragmentary vertical section taken through a superheater equipped with a throttle constructed in accordance with my invention; Fig. 2 is a fragmentary elevation taken along the line 2—2 of Fig. 1 with portions of the structure broken away for the sake of clearness, and Fig. 3 is a detail on a larger scale of the valve construction.

Referring now to the drawings, the forward end of the boiler is indicated generally at 10 with the steam dry pipe 11 passing through the forward flue sheet 12 and connecting with the saturated or inlet header 13 of the superheater located in the smoke-box 14. Steam passes from the header 13 through the superheater elements 14 located in flues 15 to the superheater or outlet

header 16, the latter being subdivided into a steam inlet chamber 17 and a steam outlet chamber 18 by the partition 19. The partition 19 is provided along its length with a plurality of ports 20 from around each of which a valve cage 21 is supported by the partition 19. The several cages 21 may, if desired, be formed integrally with the header casting but are preferably separate elements as illustrated in the figure. If made separately the cages 21 may be made a press fit in the partition, or other means for removably securing them with a steam-tight joint may be employed such as by threading or bolting.

Each cage 21 is cylindrical in form and at its open upper end is bevelled to form a valve seat 22, while the lower end is formed with a small central aperture 23. The side walls of cage 21 are provided below the partition 19 with a plurality of ports 24 providing communication between the interior of the valve cage and the steam outlet chamber 18. The valves 25 are of the poppet type, having a hollow stem extending outwardly at its lower end to form a piston 26 fitting the lower portion of the cylindrical valve cage below the level of ports 24. The length of the stem of valve 25 is such that when the valve is seated against the seat 22, the piston 26 is slightly above the bottom of the valve cage, so that a small chamber is formed between the bottom of the cage and the piston 26. The central opening 25' in the valve stem extends entirely through the valve and at its upper end there is formed a valve seat 27 adapted to receive a pilot valve 28 having a fluted stem 29 extending through the central opening 25' in the valve 25. The stem 29 is connected at its lower end to a cylindrical stem 30, the latter extending through the opening 23 in the bottom of the valve cage and being channelled near its lower end to receive a cam arm 31 attached to the operating cam shaft 32. Between the valve stem 29 and the stem 30 there is preferably secured a washer 33 larger in diameter than the opening 25' and spaced, when valve 28 is seated, a short distance below piston 26. The purpose of washer 33 is to provide a suitably large bearing surface for lifting the main valve, but this is obviously not essential, as any projection on the valve stem will serve equally well.

Above each of the ports 20 an opening 34 is provided in the upper wall of the header 16.

16, and these openings are normally closed by suitably secured cover plates 35. The sheet 36 forming the locomotive smoke-box is provided with suitable openings above the header 16, and these openings are closed by removable cover plates 37 so that access may be had through the top of the smoke-box to the valves located in the header 16.

The cam shaft 32 extends through suitable stuffing boxes from the interior of the chamber 18 to the exterior of the smoke-box, where it is connected to the throttle operating reach rod 38.

The operation of each valve is as follows: Assuming the valve to be in the position shown in Fig. 3, with superheated steam under pressure in the chamber 17, movement of the cam shaft 32 in a clockwise direction (as viewed in Fig. 3) serves to lift the pilot valve 28 and admit steam past the fluted stem 29 into the chamber formed by the bottom of the valve cage 21 and piston 26. As the piston 26 is of the same diameter as the valve 25, the latter is substantially balanced by the pressure of steam below the piston, and with the valve thus balanced further clockwise movement of the cam shaft 32 serves to lift the valve 25 from its seat through the medium of the collar or washer 33 contacting with the lower face of the piston 26. With the main valve 25 lifted from its seat, steam is then free to pass from the inlet chamber 17 through the ports 24 in the valve cage 21 to the outlet chamber 18 and from the latter to the steam pipes 39 leading to the engine.

It is to be noted that with valves constructed in accordance with my invention the entire valve structure including the balancing means is housed within the valve cage so that the entire assembly may be removed as a unit from the header for purposes of repairing or re-grinding the valves. To remove the valve 25 and the pilot valve 28, it is only necessary to remove the cover plates 37 and 35 and lift this unit out, as the cam arm 31 will slide out of the channel in the stem 30 as the latter is lifted. After the removal of valves 29 and 28 the cage, if separate and pressed into the header partition 19 as illustrated, may be removed by any suitable form of puller engaging the cage through the bottom opening 23 or the ports 24.

By the use of my invention the difficulties heretofore encountered in keeping the valves properly seated because of unequal expansion in the walls of the header casting are eliminated, as in the case of my invention the main valves 25, the balancing pistons 26

and the pilot valves 28 are all supported in a small symmetrically formed cage supported only over one narrow circumferential area so that it is not subjected to strains or distortion caused by the expansion and contraction of the header walls.

It will be apparent that the several valves may be opened serially as described in the above mentioned patent or may be simultaneously opened if desired, and it will be further apparent that the invention is applicable to throttles of a type other than that shown.

While I have, in accordance with the patent statutes, described and illustrated a specific embodiment of my invention, it is to be understood that the example I have chosen is illustrative only and that I do not limit myself thereby but may advantageously use certain elements only of the disclosure without departing from the spirit of the invention, which is furthermore to be considered as including all such changes and modifications as may fall within the scope of the appended claims.

I claim:

1. A balanced valve unit comprising a cylindrical valve cage having an open end forming a valve seat, a plurality of side wall ports and a closed end having a central opening therein, a main valve adapted to engage said seat and having a hollow stem terminating in a piston engaging said cage adjacent its closed end, a pilot valve adapted to seat in said main valve, a pilot valve stem having a fluted portion passing through said main valve stem and an extended portion passing through and closing said central opening, and a projection on said pilot valve stem adapted to engage said piston to lift the main valve.

2. In a locomotive, an elongated header, a partition dividing it longitudinally into two chambers, a plurality of aligned apertures in the partition, connections to deliver steam to one of said chambers, connections to take off steam from the other, a plurality of balanced valve units each constructed according to claim 1 and each fixed in one of said apertures, access means in the chamber wall opposite each unit through which it can be inserted and removed, the extended portions of the pilot valve stems being in alignment, a shaft in proximity to and parallel to said extended portions, a series of cams on said shaft and adapted to engage said portions and to actuate the valves when the shaft rotates.

CHARLES RINGEL.
